CLAIM

The ornamental design for a hand held scrubbing device, as shown and described.

DESCRIPTION

FIG. 1 is a top-facing perspective view of the hand held scrubbing device showing my new design;

FIG. 2 is a front elevational view thereof, the rear elevational view being a mirror image thereof;

FIG. 3 is a right-side elevational view thereof, the left-side elevational view being a mirror image thereof;

FIG. 4 is a top plan view thereof;

FIG. 5 is a bottom plan view thereof; and,

FIG. 6 is a bottom-facing perspective view thereof.

The broken lines in the figures depict portions of the hand held scrubbing device that form no part of the claimed design.
